CARD-HOLDING MEANS

Raymond E. Bauder, Chicago, Ill.

Application July 27, 1940, Serial No. 343,007

7 Claims. (Cl. 129—20)

The invention aims to provide a new and improved card-holding means especially adaptable for tenaciously holding pluralities of signature cards on pages of a record book, for use primarily by banks in checking the signatures of depositors, enabling the tellers to readily detect any possible forgeries.

In carrying out the above end, a further aim is to provide a novel relation of slits (to receive the card ends) and detents (to hold the cards in place) and in this connection, a still further aim is to so form the detents that they will not only securely hold the cards but will aid in inserting the card ends through the slits.

Another object is to provide a construction which is well adapted for holding relatively small signal cards (preferably of one or more colors) superposed upon any desired signature cards to signify anything which may be to the teller's advantage, for instance, that the depositor is in the habit of overdrawing, may have changed his address, should be consulted about one thing or another, etc.

Yet another object is to provide a book page or the like formed of two resilient sheets such as comparatively stiff paper or light cardboard, said sheets being secured together and both having the slits and detents above mentioned, providing a stiff page to carry the cards and withstand rough usage.

With the foregoing and minor objects in view, the invention resides in the novel subject matter hereinafter described and claimed, description being accomplished by reference to the accompanying drawings.

Fig. 1 is a front perspective view showing the sheet from which the preferred form of the card holder is constructed.

Fig. 2 is a rear perspective view of the sheet shown in Fig. 1.

Fig. 3 is a perspective view showing the sheet folded upon itself with its two halves secured together, providing a two-ply page to be mounted in a book.

Fig. 4 is an enlarged horizontal sectional view on line 4—4 of Figs. 3 and 7, showing more particularly the card-holding means but with no cards held thereby.

Fig. 5 is a view similar to Fig. 4 but cut on line 5—5 of Fig. 3, showing two cards held by the holding means.

Fig. 6 is another detail sectional view on line 6—6 of Figs. 3 and 7.

Fig. 7 is a sectional perspective view of the card-holding means.

Fig. 8 is a detail section illustrating the fact that the card-holding detent may have an obtuse angular end if desired.

Fig. 9 is a view similar to Fig. 8 but illustrating an acute angular end on the detent. 5

Fig. 10 is a group perspective of a number of signal or indicating cards which may be employed if desired.

The construction disclosed will be specifically explained, but within the scope of the invention, 10 variations may be made.

A book page is shown of two-ply nature, the two plies being hereinafter termed sheets 10 and 10^a. These sheets are integrally joined at one edge along a fold line 10^b, and the major portions of said sheets are secured together between the lines 11 and 11^a (Fig. 2) by means of glue, leaving each sheet with edge portions 12 and 12^a which are not glued together and are intended to receive the ends 13 of signature cards 14 when 20 said ends are inserted through slits 15 cut through said portions 12 and 12^a. Each sheet 10 and 10^a is preferably ruled off into separate areas 16 which may be consecutively numbered as shown, each of said areas having two of the 25 slits 15, disposed one in each end thereof. The two-ply page is also preferably provided with a tab 17 bearing the number of the first numbered area on said page.

Associated with each of the slits 15 is a card-engaging detent 18, and a description of one of these detents and its associated slit 15 will suffice for all, and the description will be given in connection with the sheet 10. 30

The slit 15 is preferably angular as shown, 35 with its two halves converging inwardly toward the vertical center of the sheet 10, whereby the portion of said sheet within the angle, constitutes a lip 19 having a pointed end 20. The card end 13 is to be inserted under this lip 19 40 and through the slit 15, whereby the body portion of the card will lie upon the sheet 10 and its end portions will lie under said sheet (between the two sheets 10 and 10^a in the present disclosure). Each card is preferably formed with 45 an aperture 21 into which the detent 18 snaps when the card has been inserted to the proper extent, thereby locking the card in place. The detent 18 is provided with an abrupt end 22 spaced toward the vertical edge of the sheet 10 50 from the pointed end 20 of the lip 19, said abrupt end 22 being adapted to abut one edge of the aperture 21 to securely hold the card in place. The abrupt end 22 may be at any desired angle with respect to the sheet 10. If it be at 55

right angles to the sheet (Fig. 4) or at an acute angle (Fig. 9), the card can only be removed by bodily lifting the detent-carrying portion of the sheet out of the card opening in one way 5 or another but if said abrupt end 22 be at somewhat of an obtuse angle to the sheet 10 (Fig. 8), a sufficiently hard pull upon the card will cause the detent to ride out of the opening 21. The abrupt end 22 is preferably more remote from 10 the pointed end 20 of the lip 19, than a straight line 23 extending from one end of the slit 15 to the other end of said slit (see Fig. 7). The detent thus stiffens the entire lip 19 and prevents this lip from merely having a tendency to pivot or 15 hinge upon the line 23 when it is raised somewhat during card insertion and removal. By having the detent extend into the portion of the sheet 10 beyond the line 23, said detent being itself of rather stiff nature, it is necessary that 20 said portion of the sheet 10 and the contiguous portion of the lip 19 must spring or distort somewhat when inserting and removing a card, and the end portion of the card will also be distorted or sprung to some extent. Thus, tension 25 is set up which acts to snap the detent into the card opening and to tenaciously hold the parts assembled. Even if there be no openings in the card 14, the inward friction exerted by the lip 19 and its detent 18 will be sufficient to rather 30 solidly hold the card in place.

The detent 18, in the preferred form of construction, is provided with an upwardly pressed portion 24 which inclines from the plane of the sheet 10 to the pointed end 20 of the lip 19, and 35 said detent is also provided with a portion 25 which is downwardly pressed and declines from the plane of the sheet 10 to the abrupt detent end 22. The entire detent formation is formed with appropriate dies without cutting through 40 the sheet 10 at any point, and the distortion of the sheet thus effected, stiffens the lip 19, which stiffening, coupled with location of the end 22 beyond the line 23, will insure that said lip and detent shall have the proper tension to securely 45 hold the card in position. Moreover, the upwardly pressed portion 24 of the detent 18, coupled with the angular shape of the slit 15, insure that the pointed end 20 of the lip 19 shall diverge to some extent from the upper side of 50 the sheet 10 as seen more particularly in Fig. 4, thus greatly facilitating the insertion of a card end through the slit and under the lip.

When the two-ply page construction herein disclosed is employed, the slits 15 of the sheet 55 10 are directly opposite the slits 15 of the sheet 10^a, and the detents 18 of the two sheets are directly opposite each other and in contact with each other. The detent of each sheet thus tends to force the lip 19 of the other sheet outwardly to some extent from the plane of the sheet, which aids in inserting the card ends. This outward forcing of the lips 19 also places them under quite an amount of tension causing them to tenaciously press inwardly against the 60 inserted card. In Fig. 10, I have shown a plurality of differently colored signal cards, any or all of which may be superposed upon any desired signature card 14 to call one matter or another to the teller's attention when checking a customer's signature. Each of these signal cards is formed with an opening 29 to receive the 65 detent 18 when the card is inserted under the lip 19. The signal cards are denoted at 26, 27 and 28.

75 From the foregoing, taken in connection with

the accompanying drawings, it will be seen that novel and advantageous provision has been made for carrying out the objects of the invention. While preferred details have been disclosed, variations may of course be made within 5 the scope of the invention as claimed. For example, while the slit 15 is preferably angular, it could well be of equivalent curved form.

I claim:

1. A card holder comprising a resilient sheet 10 having a slit through which to insert the end of a card, the portion of said sheet to lie upon the card end being provided with a downwardly pressed detent portion to engage an opening in the card end, said detent portion having an 15 abrupt end to abut an edge of the card opening, said detent portion being also provided with a lower side which declines from the plane of the sheet toward said abrupt end.

2. A card holder comprising a resilient sheet 20 having a slit through which to insert the end of a card, the portion of said sheet to lie upon the card end being provided with a detent portion having one of its extremities disposed at the adjacent slit and its other extremity spaced from 25 said slit, one end of said detent portion being pressed upwardly and inclined from the plane of the sheet to said one extremity, the other end of said detent portion being pressed downwardly and declined from the plane of the sheet to said 30 other extremity, the latter being abrupt to abut an edge of the card opening.

3. A card holder comprising a resilient sheet having a slit, the two halves of which converge substantially to a point whereby a portion of the 35 sheet forms a pointed lip to overlie the end of a card inserted through said slit, said lip being provided with a detent portion to engage an opening in the card end, said detent portion having one of its extremities disposed substantially at the 40 pointed end of said lip and its other extremity spaced from said pointed end, said detent being pressed downwardly and declining from the plane of said sheet toward said other extremity, the latter being abrupt to abut an edge of the 45 card opening.

4. A card holder comprising a resilient sheet having a slit, the two halves of which converge substantially to a point whereby a portion of the sheet forms a pointed lip to overlie the end of a 50 card inserted through said slit, said lip being provided with a detent portion to engage an opening in the card end, said detent portion having one of its extremities disposed at the point of said lip and its other extremity spaced from said 55 pointed end, one end of said detent portion being pressed upwardly and inclined from the plane of the sheet to said one extremity to raise the tip or point of said lip to facilitate card insertion, the other end of said detent portion being 60 pressed downwardly and declined from the plane of the sheet toward said other extremity, the latter being abrupt to abut an edge of the card opening.

5. A structure as specified in claim 3; said 65 detent being of a length to extend from said point of said lip beyond a straight line drawn from one end of said slit to the other, to stiffen said lip throughout its length and prevent it from having a tendency to merely pivot upon said line 70 when raised from its normal plane.

6. A structure as specified in claim 4; said 75 detent being of a length to extend from said point of said lip beyond a straight line drawn from one end of said slit to the other, to stiffen said lip

throughout its length and prevent it from having a tendency to merely pivot upon said line when raised from its normal plane.

5. A structure as specified in claim 1; together with a second sheet secured to the back of the aforesaid sheet, said second sheet having a slit and a detent portion duplicating those aforesaid and disposed directly opposite the same, the in-

ner sides of the two detent portions being disposed in contact with each other, whereby a card end inserted through the slit of either sheet must pass between said two detent portions and spring them apart before the opening of the 5 card end can receive one of said detent portions.
